GUIDE MEANS FOR FREIGHT CAR DOORS AND THE LIKE.

APPLICATION FILED AUG. 2, 1906.

2 SHEETS—SHEET 2.

UNITED STATES PATENT OFFICE.

THOMAS J. BRUCE, OF CHELSEA, INDIAN TERRITORY, ASSIGNOR OF ONE-EIGHTH TO WILLIAM H. CLARK, OF CHELSEA, INDIAN TERRITORY.

GUIDE MEANS FOR FREIGHT-CAR DOORS AND THE LIKE.

No. 839,721.

Specification of Letters Patent.

Patented Dec. 25, 1906.

Application filed August 2, 1906. Serial No. 328,943.

To all whom it may concern:

Be it known that I, THOMAS J. BRUCE, a citizen of the United States, residing at Chelsea, in the county of Tama, Indian Territory, have invented certain new and useful Improvements in Guide Means for Freight-Doors or the Like, of which the following is a specification.

The object of this invention is to provide novel guide mountings or parts particularly designed to be applied to freight-cars for directing the doors thereof in the movement of the latter and for substantially attaching said doors to the cars. However, it will be obvious that the invention is applicable to doors of any sliding type upon reference to the detail description hereinafter set forth.

For a full understanding of the invention and the merits thereof and also to acquire a knowledge of the details of construction of the means for effecting the result reference is to be had to the following description and accompanying drawings, in which—

Figure 1 is a perspective view showing a side of a car and the door mounted thereon in accordance with the invention. Fig. 2 is a vertical transverse sectional view taken on the line X X of Fig. 3. Fig. 3 is a longitudinal vertical sectional view taken on the line Y Y of Fig. 2. Fig. 4 is a detail perspective view of the uppermost guide members of the door. Fig. 5 is a view similar to Fig. 4, showing the lowermost guide members of the door.

Corresponding and like parts are referred to in the following description and indicated in all the views of the drawings by the same reference characters.

In the drawings, the numeral 1 designates the support to which the door 2 is attached or on which it is mounted for edgewise movement, and this support may represent the side of the freight-car. The door 1 is of the usual form, adapted to be moved back and forth in opening and closing the same and embodying any suitable lock means for holding it closed. Secured to the upper edge portion of the door is a plate 3, longitudinally of which is formed a guide-tongue 4. Pendent longitudinal edge-flanges 5 extend downwardly from the plate 3, and transversely-disposed fastenings 6 pass through the door, connect the flanges 5, and rigidly secure the guide member 3 to the door in an obvious manner. The guide-tongue 4 is

adapted to operate in a guide 7, which is attached to the support 1 above the door and which consists of a plate having spaced flanges 8 projecting downwardly therefrom to receive therebetween the tongue 4.

It will be understood that the guide 7 affords a secure bearing for the tongue 4 at the upper portion of the door and the tongue 4 is freely movable longitudinally in said guide 7. Projecting upwardly from the guide 7 are a suitable number of bracket-lugs 9, which are firmly secured to the support 1 by suitable fastenings 10. The bracket-lugs 9 are of course integral with the guides 7.

The mounting parts at the lower edge portion of the door, which receive the weight of the door mainly, are of somewhat different form than those heretofore described, though the guide member 3^a is substantially the same as the guide 3, which is secured to the top edge of the door. The tongue 4^a of the guide 3^a at the lower edge of the door, however, has a bearing in a guide 11, which is secured to the support 1 below the door 2. The guide 11 consists of a hollow body open at its upper portion and embodying the spaced sides 12, between which is received the tongue 4^a. The lower edge of the tongue 4^a is concaved transversely, so as to receive the upper portions of ball-bearings 13, which are mounted in the body of the guide 11, said body being of somewhat circular form in cross-section in order to conform with the shape of the ball-bearings 13 somewhat, so that the latter will travel snugly in the guide 11. The ball-bearings 13 are arranged at suitable intervals in the length of the guide 11, and a dozen or more of the balls are located at such intervals. In the length of the guide 11 the body of said guide is formed with partitions 14, which separate the sets of ball-bearings, as will be evident by reference to Fig. 3 of the drawings. The door 2 of course travels smoothly on the ball-bearings 13 and may be opened with considerable ease for obvious reasons. Opposite end portions of the upper guide 7 and the lower guide 11 are closed, as shown at 15 and 16, respectively. The guides 7 and 11 are preferably twice as long as the guides which are attached to the door, by reason of the length of travel of the door necessitated by its opening and closing movement.

Suitable bracket-lugs 9^a are also projected

downwardly from the guide 11 in order to secure the same firmly to the support 1.

Having thus described the invention, what is claimed as new is—

- 5 1. In combination with a suitable support, a door mounted thereon, guide means at the upper portion of the door, guide means at the lower portion of the door embodying a guide-tongue projecting from this portion of the door and suitably secured thereto, a guide secured to the support below the lower end of the door and consisting of a hollow body, receiving the tongue attached to the lower extremity of the door, means securing said lower guide to the support, and ball-bearings mounted therein.
- 10 2. In combination, a support, a door mounted for edgewise movement thereon, guide means at the upper end of the door, guide means at the lower end of the door em-

bodying a guide-tongue secured to the lower edge portion of said door, a lower guide attached to the support below the door and receiving the tongue aforesaid, said lower guide comprising a hollow body closed at its end ²⁵ portions and embodying sides embracing the sides of the tongue on opposite sides, the lower guide being divided by partitions into a number of ball-bearing seats, and ball-bearings in contact with the lower edge of the ³⁰ tongue and mounted in the several seats at intervals in the length of the lower guide in the manner specified.

In testimony whereof I affix my signature in presence of two witnesses:

THOMAS J. BRUCE. [L. S.]

Witnesses:

JOHN T. EZZARD,
WILLIAM H. CLARK.
